UNITED STATES PATENT OFFICE

GODFRIED LAUBE, OF SANTA MONICA, CALIFORNIA, ASSIGNOR OF ONE-HALF TO JOHN C. MILLER, OF LOS ANGELES, CALIFORNIA.

UMBRELLA-STAND.

No. 852,567.

Specification of Letters Patent.

Patented May 7, 1907.

Application filed August 18, 1906. Serial No. 330,357.

To all whom it may concern:

Be it known that I, GODFRIED LAUBE, a citizen of the United States of America, residing at Santa Monica, in the county of Los Angeles and State of California, have invented certain new and useful Improvements in Umbrella-Stands, of which the following is a specification, reference being had therein to the accompanying drawing.

This invention relates to certain new and useful improvements in an umbrella stand designed for use upon a porch, veranda or similar place.

The object of this invention is to provide a simple and inexpensive article, which will be neat and present an attractive appearance.

The detail construction of my improved article will be presently described, illustrated and then specifically pointed out in the appended claims.

Referring to the drawing forming part of this specification, Figure 1 is a perspective view of my improved article as used upon a porch, Fig. 2 is a longitudinal sectional view 25 of the same, and Fig. 3 is a cross sectional view of the article.

The device embodies a platform 1, having a plurality of longitudinally disposed grooves 2 formed therein, but it is obvious that the 30 platform can be constructed of a plurality of slats suitably connected together, as by molding strips 3. The platform is preferably placed in front of a door 4, upon a porch 5 and directly in front of the door I provide the 35 platform 1 with a mat or rug 6, said mat being of an ordinary form composed of bristles or fabric. The mat is detachably held upon the platform by molding strips 7 secured to said platform and surrounding the mat or 40 rug.

At the end of the mat or rug 6, upon the platform I secure a basin or pan 8, which can be made of galvanized iron or tin and painted or japanned. Centrally of the basin or pan, 45 I erect a stationary foot scraper 9 of an ornamental design, this scraper being used to remove mud and dirt from shoes, the dirt and mud being collected in the basin or pan 8 surrounding the scraper.

The umbrella holder is erected at the extreme end of the platform opposite the mat or rug 6. The holder 10 is constructed of wire bent and twisted to form two standards 11 having their ends secured in the platform, as at 12. The wires forming the upper ends of the standards are bent to form two loops or retainers 14, which are connected together, by a bridge 15, from which a suitable plate 16 can be suspended bearing an advertisement or sign, such as "Wipe your feet." The loops or retainers 14 are employed to support umbrellas in a substantially vertical position, whereby they may drain, if wet from rain. The platform 1 beneath each loop or retainer 14 is provided with a recess or depression 17, to accommodate the tips of umbrellas.

To prevent the mat or rug 6 from becoming water-soaked, foul and eventually disintegrated, I provide the platform 1 beneath the mat or rug with openings 18 to allow water to pass through the mat or rug and the platform.

It is apparent from the foregoing description, taken in connection with the drawing, that my improved article is extremely useful in rainy weather, and protects the interior of a house from mud, dirt and water, that would otherwise be carried in the house.

What I claim and desire to secure by Letters Patent, is:—

In a device of the character described, a supporting platform, and a rack mounted thereon and formed from two strands of wire twisted together to form two vertical standards, the wires forming the standards being separated at their lower ends and secured in the base, and at their upper ends each having a loop, and a bridge connecting the loop of one standard to the loop of the other standard.

In testimony whereof I affix my signature in the presence of two witnesses:

GODFRIED LAUBE.

Witnesses:

HATTIE ROSE LAUBE,
J. E. MILES.
